(57) **CLAIM**

The ornamental design for a pendant, as shown and described.

DESCRIPTION

FIG. 1 is a top front side perspective view of a pendant showing my new design;

FIG. 2 is a front view of the pendant, a rear view being a mirror image thereof;

FIG. 3 is a right side view of the pendant, a left side view being identical; and,

FIG. 4 is a front side perspective view of the pendant. The broken lines are illustrative of portions of the pendant forming no part of the claimed design.
